UNITED STATES PATENT OFFICE.

CHRISTIAN RUDOLPH MUELLER, OF HIGHLAND PARK, MICHIGAN.

ELECTRIC-PLUG ATTACHMENT.

Application filed March 4, 1923. Serial No. 540,986.

My invention relates to electric plug attachments and more particularly to an attachment adapted to be connected with the ordinary electric light socket for the purpose of utilizing the electric wiring system as a radio receiving antenna.

It is one of the prime objects of my invention to provide a device which may be utilized by the ordinary individual in his home as an aerial for receiving wireless messages, the intent being to utilize the vast amount of wiring used in an electric system for the purpose of gathering radio signals which make possible the use of wireless receiving apparatus. It is impracticable to utilize the ordinary electric lighting circuit as an antenna for a radio receiving outfit because of the dangerous currents carried by the electric lighting circuit. My improved device will make safe the use of the ordinary electric wiring system of a house because of the fact that I interpose a means to prevent dangerous currents from entering the radio set.

It is a further object of my invention to provide such means of cheap and simple construction and wherein all possibility of electric shocks or other accidents is removed.

With these and other objects in view, my invention consists in the arrangement, combination and construction of the various parts of my improved device as described in the specification, claimed in my claims, and shown in the accompanying drawings, in which:

Fig. 1 is an elevation of my improved device together with an ordinary electric light plug socket.

Fig. 2 is a sectional view of my improved device.

Fig. 3 is a view showing the material used in a condenser for my improved device and

Fig. 4 is a sectional view taken on line 4-4 of Fig. 2.

I have shown an ordinary standard electric light plug socket 1, having a head 2 thereon into which the conductors 3 and 4 of a plug are adapted to seat. I have shown the conductors 3 and 4 mounted in an insulating member having a head 5 and a body portion 6.

Within the body portion 6, I provide a condenser 7 which is constructed of two sheets of conductive material such as tin or copper foil 8 and 9 and separated by a suitable di-

electric such as paraffin paper, mica or em- 55 pire cloth 10.

The conductors 3 and 4 are suitably secured in the head 5, as by means of screws 11 and 12. Running from one of these conductors, as herein shown from the conductor 3, 60 I provide a conductor 22 which is suitably secured to either one of the conductors 8 and 9, say to the conductor 8 as at 13. I then provide a conductor 14 suitably attached to the other of the conductors 8 and 9, as in this 65 instance to the conductor 9, as at 15. The incoming radio signals will pass on through the conductor 14 into the radio receiving set or other similar apparatus.

Condenser 7 provides an inductive coupling between the electric lighting circuit and the receiving apparatus of such value that the direct or low frequency currents flowing in the ordinary electric lighting circuit cannot pass through to such apparatus. The construction of the condenser is such that, while blocking the low frequency currents carried by the supply system, high frequency radio currents are permitted to pass.

In some cases it may be desirable to so 80 label or mark the heads 2 and 5 of the separable plug so that they may be joined to the same support whenever the device is used.

It will thus be seen that undesirable current from the ordinary lighting circuit can- 85 not pass through the condenser 7. The construction of the condenser 7 is such that high frequency radio currents can pass there- through and on, via conductor 14, to the ra- 90 dio receiving set, where they will be "select- ed", "detected" and "amplified" to any degree desired.

It will be seen that only one side of the lighting circuit is utilized as with conductor 3, the other conductor 4 being dead. The 95 dimensions of the two conductors 3 and 4 being identical and proportioned to match the standardized plug receptacle, the device can be reversed until by trial the best position can be determined. In some cases it may 100 be desirable to so label or mark the heads 2 and 5 that they may always be joined in same position after being separated. This is because the two sides of an ordinary light- 105 ing circuit have different characteristics when used as a radio antenna.

It is obvious that various changes may be made in the arrangement, combination and

construction of the various parts of my improved device without departing from the spirit of the invention therein and it is my intention to cover by my claims such changes 5 as may be reasonably included within the scope thereof.

What I claim is:

1. In a device of the class described, a conventional electric lighting socket plug, a second plug having a pair of prongs for insertion in said socket plug, a condenser secured to said second plug and electrically connected to one of said prongs, and means for connecting said condenser with a radio receiving set.
- 10 2. In a device of the class described, a conventional electric lighting socket, a condenser adapted to be connected at one end with a radio receiving set, a covering for said condenser, means for engaging said outlet comprising a pair of prongs secured to said covering, one of said prongs being electrically connected with said condenser.
- 15 3. In a device of the class described, a condenser, an insulated housing for said condenser, means leading from said condenser for connecting it with a radio receiving set, a conventional electric lighting socket plug having two openings therein, a reversible or secondary plug integral with said housing, 20 said second plug having a pair of prongs properly spaced for simultaneously entering said openings in the socket plug, and means for connecting one of said prongs with said condenser.
- 25 4. In a device of the class described, a conventional electric lighting socket plug, a second plug comprising a housing of insulated material having a pair of prongs secured in one end thereof adapted to be inserted into 30 said socket plug, a condenser in said housing and electrically connected with only one of said prongs, an electric conductor adapted for attachment to a radio receiving set connected at one end to said condenser, whereby 35 one side only of a lighting circuit may be connected with a radio receiving set and no electric shock from said circuit may be sustained.
- 40 5. In a device of the class described, a conventional electric lighting socket, a plug for said socket comprising a cylindrical housing of insulating material having a pair of prongs secured in one end thereof, a condenser rolled in cylindrical form into said housing, an insulated conductor leading from said housing

and connected with said condenser and means 55 for connecting one only of said prongs with said condenser.

6. In a device of the class described, a conventional electric lighting socket plug, a condenser adapted to be connected at one end 60 with a radio receiving set, an insulated housing for said condenser, a second plug integral with said housing, a pair of prongs secured to said second plug adapted to be inserted into said socket plug and one of said prongs being 65 directly connected with said condenser.

7. A device for inductively coupling high frequency signalling apparatus to an outlet of a system carrying direct or relatively low frequency currents, said device comprising a condenser having a value which will pass high frequency currents but prevent the flow of direct or low frequency currents, an insulating casing for said condenser, a terminal for the condenser secured to the casing and adapted 70 to engage said outlet, and means for connecting the condenser with said signalling apparatus.

8. A plug for inductively coupling a high frequency receiving set to a conventional outlet of a system carrying direct or relatively low frequency currents, said plug comprising a condenser having a value which will pass high frequency currents but prevent the flow of direct or low frequency currents, a casing 85 of insulating material for said condenser, a plurality of members secured to the casing and adapted to engage said outlet, certain 90 of said members comprising one terminal of the condenser, and means comprising another terminal of the condenser for connecting the same with said receiving set.

9. A plug for inductively coupling a high frequency receiving set to a conventional outlet of a system carrying direct or relatively 95 low frequency currents, said plug comprising a condenser having a value which will pass high frequency currents but prevent the flow of direct or low frequency currents, a casing of insulating material for said condenser, a plurality of members secured to one end of the casing and adapted to engage said outlet, certain of said members comprising one terminal of the condenser, means comprising the other terminal of the condenser being secured to the opposite end of the casing for connecting the plug with said receiving set.

C. RUDOLPH MUELLER.
